UNITED STATES PATENT OFFICE.

WILLIAM BRUCE WRIGHT, OF LIVERPOOL, ENGLAND.

MEANS FOR CLEANING, SCALING, OR CHIPPING SURFACES.

Application filed March 29, 1923. Serial No. 628,673.

To all whom it may concern:

Be it known that WILLIAM BRUCE WRIGHT, of 75 Merton Road, Bootle, Liverpool, England, whose residence is 75 Merton Road, Bootle, Liverpool, England, and a subject of the King of Great Britain and Ireland, has invented certain new and useful Improvements in Means for Cleaning, Scaling, or Chipping Surfaces, of which the following is a specification.

This invention has for its object to provide a light, compact and portable machine adapted for cleaning, scaling, or chipping surfaces, the machine being suitable for operation by electric, pneumatic, mechanical or other power.

The improved apparatus forming the subject matter of the present invention comprises a rotary shaft adapted to receive and drive a rotary member or hammer having striker projections adapted to act upon a reciprocating tool for operating upon the surface under treatment, a casing within which said rotary member and tool are mounted, said casing having guide means in which the bearings of the shaft are supported in a manner allowing slight movement of the shaft towards and from the surface operated upon.

The rotary shaft may be coupled to an electric motor or a pneumatic motor attached to the apparatus and controlled by a local switch or valve or may be connected with a flexible drive shaft transmitting power from a relatively fixed source.

The invention is hereinafter more fully described with reference to the accompanying drawings in which:—

Figs. 1 and 2 are respectively a side elevation partly in section and an end sectional elevation of a tool constructed according to this invention.

The improved tool comprises a casing *a* with a pair of parallel guide ways *c* in its opposite sides in which the ball bearings *d* of a shaft *e* are mounted and pressed by springs *f* in the direction of the reciprocating

tool *p*. Detachably fitted within a hollow neck *o* on the casing is a sleeve *o'* forming a guide for the reciprocating tool *p* while the driving shaft *e* carries the rotary hammer *g* having striker projections *g'* which actuate said tool.

The tool *p* is formed or provided with an enlarged head *q* whose upper face co-operating with the strikers *g'* is preferably inclined slightly (say about 2°) to the plane perpendicular to the line of reciprocation of the tool. A helical spring *r* interposed between the head *q* and the upper end of the guide sleeve *o'* resiliently supports the tool and holds its head *q* in the path of the strikers *g'*.

For facilitating the assembly of the parts or the removal of the shaft *e*, bearings *d* and rotating member *g* from the casing the guide ways *c* are open at their upper ends but normally closed by a detachable cover plate *a'* secured by screws in the head of the casing.

A laterally disposed tubular handle (not shown) may be attached to the casing and enclose the connection of the shaft *e* with the flexible driving shaft as previously referred to.

If preferred the tool may be operated by an electric or pneumatic motor attached to the casing itself and coupled directly to the shaft *e*, the motor being supplied with power by flexible leads or by a pipe.

I claim,

Apparatus for cleaning, scaling or chipping surfaces comprising a casing, parallel guide ways in the sides of the casing, bearings mounted in the guide ways, cushioning springs arranged to act on the bearings, a rotary shaft mounted in the bearings, a rotary hammer mounted on the shaft and actuated thereby, and a reciprocating tool resiliently supported in the casing in the path of the hammer.

In testimony whereof he has affixed his signature.

WILLIAM BRUCE WRIGHT.
